ACCESSORY FOR INTERNAL COMBUSTION ENGINE

Hugo R. Gallun, Salem, Oreg., assignor to Smog Co., a corporation of Nevada

Application January 15, 1954, Serial No. 404,356

2 Claims. (Cl. 251—129)

This invention relates generally to internal combustion engines, and has for its primary object the provision of valve mechanism to be utilized in conjunction with the carburetor of an engine to prevent fuel from "loading up" in an engine during such times as the carburetor throttle valve is in closed position and the engine is being utilized as a brake.

In addition to the above mentioned object, a further object is to provide an air bleed valve assembly for bypassing a carburetor which is controlled by the operator of a vehicle.

Still another object of this invention is to provide an air bleed attachment for carburetors which is readily applied to existing manifold assemblies and requires no special equipment in its use.

Another object of this invention is to provide a mechanism of the character described which is possessed of rapid opening and closing characteristics and which will be substantially noiseless in operation.

These together with other objects and advantages which will become subsequently apparent reside in the details of construction and operation as more fully hereinafter described and claimed, reference being had to the accompanying drawings forming a part hereof, wherein like numerals refer to like parts, and in which:

Figure 1 is a side elevational view of an internal combustion engine showing the attachment in place;

Figure 2 is a horizontal section taken substantially along the plane of section line 2—2 of Figure 1;

Figure 3 is an enlarged view, partly in section, of the attachment;

Figure 4 is a perspective view of the valve body member;

Figure 5 is a view of the attachment with portions thereof broken away to show the valve body in closed position; and

Figure 6 is a diagrammatic view showing a portion of the electrical circuit for controlling the accessory attachment.

Referring now more particularly to Figure 1, reference numeral 10 indicates generally the block of an internal combustion engine provided with the usual head 12 and with the conventional intake manifold assembly 14, exhaust manifold assembly 16 and preheater chamber 18 upon which is mounted the carburetor assembly 20 provided with its usual air filter member 22. The conventional manner of mounting the carburetor 20 on the preheater 18 is by the provision of stud members threaded into the latter which project through suitable openings on the flange 24 of the carburetor, nuts being engaged on the upper ends of the studs for removably securing the carburetor in place.

To utilize the invention, it may be necessary to replace the conventional carburetor attaching studs with longer studs so that the flange portion 26 of the adapter 28 may be secured in position between the preheater and the carburetor flange, these studs being indicated by the ref-

2

erence character 30. It will be seen that the adapter 28 includes the previously mentioned flat flange 26 which has a bore 32 therethrough mating with both the carburetor and preheater bores or openings and a conduit portion 34 which may be of elbow configuration to properly position the attachment, the passage 36 of the elbow intersecting the bore 32 to communicate with the fuel air passage of the intake manifold. The free end of the adapter is provided with a flange 38 by means of which it is detachably secured to the flange 40 of the air bleed valve assembly indicated generally by the reference character 42.

As seen most clearly in Figure 3, the air bleed valve assembly incorporates a horizontally extending neck portion 44 having the previously mentioned flange 40 at its free end and extending from the body of the valve assembly, in the manner shown. The valve assembly is also provided with an air horn 46 and its interior is hollow and has upper and lower horizontal partition walls 48 and 50 extending from side to side thereof and connected at one end with a vertical wall member 52 so as to provide the chamber 54 which opens into the interior of the valve body and in communication with the air horn 46 through openings 53 and 55 in the upper and lower wall members, respectively. Thus, it will be seen that the carburetor 20 may be by-passed by introducing air through the air horn 46 of the air bleed valve assembly 42, through the adapter 28 and directly into the intake manifold below the carburetor.

For controlling such flow of air, the valve member 56 is provided which is secured to a plunger shaft 58 extending from plunger 60 of solenoid assembly 62 for vertical reciprocation under action of the solenoid, when energized, and the weight of the valve mechanism as a whole when the solenoid is de-energized.

As seen most clearly in Figure 4, the valve 56 embodies a tubular shank 64 having upper and lower valve heads 66 and 68 at its opposite ends movable into and out of the openings 53 and 55, respectively, the open position being shown in Figure 3, while the closed position is shown in Figure 5.

The solenoid assembly is removably secured to the bottom of the air bleed assembly 42, as by the fastener 70, such that the plunger shaft 58 is in concentric alignment with openings 53 and 55. The shaft extends entirely through the assembly 42 and is threaded at its upper free end 71 to receive the lock nut 72 below which a metal washer 74 and a resilient bumper washer 76 are respectively disposed. The top of the assembly 42 is provided with an enlarged opening 78 through which the valve 56 may be inserted, the valve shank having a transverse bore therethrough, as does the plunger shaft, for receiving a lock pin 80 for securing these parts together.

A cover 82 is removably secured to the assembly 42 over the opening 78 and the lock nuts 72 are so adjusted that the valve heads 66 and 68 are in their associated openings 53 and 55 when the bumper 76 rests upon the cover 82. The shaft portion 71 is of reduced diameter to provide a shoulder upon which the metal washer 84 rests, the resilient bumper washer 86 resting upon the latter and being engaged against the undersurface of the cover 82 when the solenoid is energized to limit the upward movement of the valve 56. When the solenoid is energized, it will be noted that the circumferentially spaced depending guide fingers 88 and 90 on the valve heads 66 and 68 remain in guiding contact with the surfaces of the walls 48 and 50 defining the openings 53 and 55 so that the valve assembly, when the solenoid is de-energized, will be properly guided back into sealing relation to the wall openings with as rapid a movement as possible.

By the provision of the dual openings 53 and 55 and the dual valve assembly 56 having the two head portions 66 and 68, it will be manifest that a very rapid and unrestricted communication between the air horn 46 and the adapter 28 will be effected upon energization of the solenoid assembly 62.

For energizing the solenoid assembly 62, a switch member 91 is mounted on the carburetor 20 adjacent the throttle valve actuating lever 93 so that when the accelerator linkage 92 is in the position of the full lines of Figure 1, that is, the closed position of the throttle valve, the switch 91 will be actuated to permit the solenoid to be connected to a source of electrical current through the lead 94, switch 91, lead 96, dash control switch 98 and lead 100. The dash control switch is provided for operation under control of the operator of the motor vehicle so that the valve cannot be opened when the engine is cold. Lead 100 is connected, through a solenoid switch 102, to a generator 104 driven by the engine. The contact member 106 of the solenoid switch is spring urged to the open position and the spring is of such strength that when the engine is idling the output of generator 104 will be insufficient to overcome the force of the spring. Thus, at some speed close to the normal idling speed of the engine, the solenoid 62 cannot be energized to open the valve assembly.

Any conventional air filter 108 may be used on the air horn 46, as desired.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claims.

What is claimed as new is as follows:

1. An air bleed valve assembly for internal combustion engines comprising, a hollow casing having an air horn opening thereinto and an outlet neck, upper and lower partition walls providing a chamber separating the outlet neck from the air horn, said upper and lower walls each having openings therethrough and said casing having apertures in the opposing walls thereof aligned with said partition wall openings, a plunger shaft extending vertically through said casing and chamber and having its ends disposed exteriorly of said casing, solenoid means for moving said shaft upwardly mounted ex-

teriorly of said casing and attached to one end of said shaft, and a vertically reciprocable valve mounted on an intermediate portion of said shaft having upper and lower piston-like head portions movable into and out of said openings to sealingly engage the side walls of said openings to establish and disestablish communication between said air horn and said outlet neck, and spaced resilient bumper means on said shaft adjacent the end thereof opposite said one end for limiting the upper and lower positions of said valve, said bumper means being disposed interiorly and exteriorly of said casing, means on said shaft for adjusting the position of the exterior bumper means along said shaft.

2. An air bleed valve assembly for internal combustion engines comprising, a hollow casing having an air horn opening thereinto and an outlet neck, upper and lower partition walls providing a chamber separating the outlet neck from the air horn, said upper and lower walls each having openings therethrough and said casing having apertures in the opposing walls thereof aligned with said partition wall openings, a plunger shaft extending vertically through said casing and chamber and having its ends disposed exteriorly of said casing, solenoid means for moving said shaft upwardly mounted exteriorly of said casing and attached to one end of said shaft, and a vertically reciprocable valve mounted on an intermediate portion of said shaft having upper and lower piston-like head portions movable into and out of said openings to sealingly engage the side walls of said openings to establish and disestablish communication between said air horn and said outlet neck, said valve heads having circumferentially spaced guide fingers engaging with the surfaces of said walls defining said openings, and spaced resilient bumper means on said shaft adjacent the end thereof opposite said one end for limiting the upper and lower positions of said valve, said bumper means being disposed interiorly and exteriorly of said casing, means on said shaft for adjusting the position of the exterior bumper means along said shaft.
